SOLDERING PISTOL

Rinze P. Elzinga, Nijkerk, Netherlands, assignor to
Technische Industrie Elko N.V., Nijkerk, Netherlands

Filed Nov. 20, 1969, Ser. No. 20,193

Term of patent 7 years

Int. Cl. D8—02

U.S. Cl. D8—30

FIG. 1 is a perspective view of the soldering pistol showing my new design;

FIG. 2 is a side elevation view of the opposite side of the invention;

FIG. 3 is a top plan view of the invention; and

FIG. 4 is a front elevation view of the invention.

The broken line disclosure of a power cord in FIGS. 1, 2 and 4 is for illustrative purposes only.

I claim:

The ornamental design for a soldering pistol, substantially as shown and described.
